UNITED STATES PATENT OFFICE.

FLORENCE MYRA COHAN, OF OAKLAND, CALIFORNIA.

DEPILATORY COMPOUND.

No Drawing. Application filed January 31, 1917, Serial No. 145,731. Renewed July 14, 1923.

To all whom it may concern:

Be it known that I, FLORENCE MYRA COHAN, a citizen of the United States, residing at Oakland, in the county of Alameda and State of California, have invented certain new and useful Improvements in Depilatory Compounds, of which the following is a specification.

This invention is a compound for treating the face to eliminate hair permanently therefrom.

The compound includes two sub-compounds, one sub-compound for removing the hair from the face, and another sub-compound for preventing further growth of hair after the hair has been removed.

The compound includes the following ingredients in the proportions substantially as indicated:

20 Rosin	3 pounds
Beeswax	1 pound
Oil of cloves	2 drachms
Lime water	16 ounces
Oil of terebinthinae	16 drops
Peroxide of hydrogen	1 drachm
Tincture of cudbear	30 drops
Oil of garden lavender	25 drops

These ingredients are combined as follows:

The rosin is placed in a sterilized vessel and allowed to melt at a low temperature, preferably over a water bath. In the meantime the wax is melted in a separate vessel and the rosin is slowly added thereto, the two being thoroughly mixed by stirring. The mixture of rosin and wax is then allowed to remain heated for fifteen minutes at a moderate temperature, but at no time is it allowed to boil. It is then allowed to cool for ten minutes and before it loses its fluidity two drachms of oil of cloves is added. This is thoroughly mixed and the resultant product is poured into moulds and allowed to cool. This combination consti-

tutes the sub-compound for removing the hair.

The lime water and oil of terebinthinae are thoroughly mixed by agitation or shaking, and then are added the peroxide of hydrogen and oil of lavender and tincture of cudbear. These ingredients are all thoroughly mixed by shaking and bottled separately from the rosin and waxed mixture. This combination constitutes the sub-compound for application to the skin after the hair is removed to prevent further growth of hair.

In using the above composition the mixture of wax and rosin are first slightly heated and applied to the spot over which it is desired to remove the hair. This is allowed to remain until it has been cooled, when by quick motion it is removed, carrying with it the hair from that spot. This leaves the hair duct open when the liquid second mentioned is applied and is readily absorbed by the open hair duct and harmlessly prevents the further growth by its action on the roots.

I claim as new and wish to cover by Letters Patent:—

1. A compound consisting of a major portion of lime water and smaller portions of oil of terebinthinae, and peroxide of hydrogen, said compound preventing the growth of hair on surfaces from which hair has been removed, and for soothing said surface.

2. A compound for use in depilatory treatments consisting of a major portion of lime water, smaller portions of oil of terebinthinae and peroxide of hydrogen mixed with desired proportions of tincture of cudbear and oil of lavender, said compound preventing the growth of hair and soothing rough surfaces of the skin.

In testimony whereof I affix my signature.

FLORENCE MYRA COHAN.
